(57) **CLAIM**

The ornamental design for a display screen portion with graphical user interface, as shown and described.

DESCRIPTION

FIG. 1 is a front view of a first embodiment of a display screen portion with graphical user interface showing my new design; and,

FIG. 2 is a front view of a second embodiment of a display screen portion with graphical user interface showing my new design.

The broken line showing of the display screen in FIGS. 1 and 2 forms no part of the claimed design. The broken line showing of the remainder of the graphical user interface in the FIGS. 1 and 2 represents environmental subject matter and forms no part of the claimed design.

1 Claim, 2 Drawing Sheets**FIG. 1**

FIG. 2
